UNITED STATES PATENT OFFICE.

WALLACE A. MARTINDALE, OF CHARLESTON, SOUTH CAROLINA.

POISON-CONTAINER.

1,254,616.

Specification of Letters Patent. Patented Jan. 22, 1918.

Application filed April 17, 1916. Serial No. 91,823.

To all whom it may concern:

Be it known that I, WALLACE A. MARTINDALE, citizen of the United States, residing at Charleston, in the county of Charleston and State of South Carolina, have invented new and useful Improvements in Poison-Containers, of which the following is a specification.

This invention relates to poison containers, and it has for its object to produce a simple and improved device whereby the actual container is provided with a casing which may be detached only in a certain specified way and which, when in position, renders access to the contents impossible.

A further object of the invention is to produce an improved poison container comprising a receptacle and a casing for the same, said receptacle and casing being provided with interengaging locking members of simple and improved construction.

With these and other ends in view which will readily appear as the nature of the invention is better understood, the same consists in the improved construction and novel arrangement and combination of parts which will be hereinafter fully described and particularly out in the claim.

In the accompanying drawing has been illustrated a simple and preferred form of the invention, it being, however, understood that no limitation is necessarily made to the precise structural details therein exhibited, but that changes, alterations and modifications within the scope of the claim may be resorted to when desired.

In the drawings:—

Figure 1 is a view in side elevation of the improved poison container.

Fig. 2 is a side elevation showing the poison receptacle detached from the outer casing.

Fig. 3 is a vertical sectional view taken on the line 3—3 in Fig. 1.

Fig. 4 is a horizontal sectional view taken on the line 4—4 in Fig. 1.

Corresponding parts in the several figures are denoted by like characters of reference.

The poison receptacle is in the form of a bottle A which may be made of glass or other suitable material, the walls of the receptacle being of sufficient thickness to permit the formation therein of certain locking grooves which will be presently described. The receptacle or bottle is provided near its lower end with a circumferential offset 15, and it

has at its upper end a shoulder 16 from which rises the neck 17 which is provided with a stopper; preferably a screw cap 18, although any convenient stopper may be used. The wall of the receptacle is provided in the outer face thereof with a vertical groove 19 extending between the shoulder 16 and the offset 15. Adjacent to said offset is formed a horizontal groove 20 which communicates at one end with the groove 19. The top wall of the groove 20 has an upwardly extending recess 21, and extending upwardly from the offset 15 midway between the ends of the recess 21 is a lug 22, the top edge of which lies in the plane of the top wall of the groove 20. The recess 21 is spaced from the groove 19 by a lug 23 which is similar to the lug 22, the lower edge of the lug 23 lying in the plane of the top edge of the lug 22.

The external casing B of the improved device consists of a shell made preferably of metal, the same having at its upper end a neck 24 adapted to receive the neck 17 of the receptacle or a portion of said neck and having a closure, preferably a screw cap 25. The shell B is provided at its lower end with a circumferential flange 26 producing a shoulder or offset 27 adapted to engage the offset 15 of the receptacle A. The shell or casing B is provided with an internally disposed lug 28 which is of such dimensions that it will readily engage the grooves 19, 20 of the receptacle.

It will be observed that the grooves 19, 20 in the outer face of the walls of the receptacle, together with the recess 21 and lugs 22, 23, produce an angular passageway through which, when the casing B is assembled with the receptacle A, the lug 28 may travel, it being necessary to give certain predetermined twists to the casing relatively to the receptacle in order to enable the lug 28 to follow the convolutions of the passageway. While, therefore, not absolutely necessary, it is at least desirable that the operator should be previously acquainted with the particular convolutions of the passageway in order that the receptacle and the casing may be readily assembled and disassembled. This is a precaution against the convenient disassembling of the receptacle and the casing by unauthorized persons. In some instances it may be found preferable that the contour of the passageway in the receptacle should be exposed, and in such case the external shell

may be formed of glass or transparent material.

In assembling together the herein described shell or casing with the receptacle the lug 28 is first brought in registry with the outer end of the groove 19, after which the casing is slid lengthwise of the receptacle, the latter being held by the left hand of the operator while the casing is supported 10 by the right hand. When the lug 28 strikes the offset 15, the receptacle and casing are relatively twisted in opposite directions to move the lug 28 in the direction of the lug 22. An outward movement of the casing 15 will now slide the lug 28 into the recess 21 until it abuts on the upper wall of said recess. A twisting movement is now required to move the lug 28 past the lug 22 until it strikes the end wall of the recess 21, after 20 which the receptacle is again pushed inward with respect to the casing until the lug 28 strikes the offset 15. A final twisting movement of the receptacle with respect to the casing will now cause the lug 22 to travel 25 within the horizontal groove 20 until it strikes the inner end wall of said groove when the receptacle and the casing will be locked together. A reversal of the operation is required to separate the casing from the 30 receptacle.

It is obvious that within the scope of the invention the shape or contour of the groove or passageway formed in the receptacle for the passage of the lug 28 may be materially 35 changed and made more or less intricate than herein described.

When the casing is assembled with the receptacle it will obviously be impossible for anyone to dispense the contents of the receptacle without having ample warning of 40 the nature of the contents. It thus becomes absolutely impossible to dispense the poisonous contents of the receptacle accidentally or otherwise than with full knowledge and 45 intention.

It may be stated that the purpose of providing the screw cap or false stopper 25 is this, that a person picking up the receptacle will naturally first remove the said screw

cap and will thus to all appearances find 50 the receptacle empty. It is believed that children will rarely continue the investigation further, but will rather be inclined to replace the stopper. In the case of adults attempting to gain access to the contents by 55 removing the false stopper, that alone would give ample warning that the receptacle or device is one which is not to be tampered with. The said false stopper, therefore, constitutes an additional and very important 60 safeguard to give warning that the receptacle and the contents thereof is not to be tampered with.

Having thus described the invention, what 65 is claimed as new, is:—

A poison container comprising a receptacle having an external annular offset, said receptacle having also a shoulder and a neck rising therefrom, said receptacle being provided in the outer face thereof with an uninterrupted vertical groove extending between the shoulder and the offset and adjacent to said offset with a horizontal groove communicating at the lower end with the vertical groove, the top wall of said horizontal groove having an upwardly extending substantially inverted U-shaped recess, the bottom wall of the horizontal groove having a lug extending in the direction of said recess between the ends thereof, and said recess being separated from the vertical groove by a lug that extends downwardly with respect to the top wall thereof, said grooves, recess and lugs combining to form a tortuous channel; in combination with a shell or casing having at its lower end an annular flange producing a shoulder or offset to engage the offset of the receptacle, said shell having an interiorly disposed lug adapted for engagement with the tortuous 90 channel of the receptacle; said shell having a shoulder and neck provided with a detachable closure.

In testimony whereof I affix my signature.
WALLACE A. MARTINDALE.
